ELECTRIC TORCHES

Wing G. Cheng, Kowloon, Hong Kong, assignor of one-half to Meyer Manufacturing Company Limited, Kowloon, Hong Kong

Application June 22, 1956, Serial No. 593,256

Claims priority, application Great Britain November 9, 1955

5 Claims. (Cl. 240—10.66)

This invention relates to portable electric illuminating devices of the kind supplied by a dry battery and usually termed electric torches.

The object of the invention is to provide a device of the above kind fitted with a lamp bulb at each end and with a switch for selectively switching on either one of the lamp bulbs and which can be used either as a hand torch or, when desired, as a table lamp by standing the device on one end, the lamp at this end being extinguished whilst the lamp at the other end is illuminated, and in which means are provided for ensuring that the switch is not moved accidentally from the "off" position to either one of the "on" positions.

A further object of the invention is to provide simple and reliable electrical connections between the switch and the two lamps and between the latter and the positive and negative terminals of the supply battery.

In the accompanying drawings which illustrate how the invention may be carried into effect:

Fig. 1 is a view in elevation partly in section, of a torch construction having a lamp bulb at each end which can be selectively illuminated and which can be used in the ordinary way as a hand torch or can be stood on one end to provide a table lamp.

Figs. 1a and 1b are respectively end views of the opposite ends of the device;

Figs. 1c and 1d are detail views illustrating the switch in the two different "on" positions;

Fig. 2 is a cross-section taken on line IV—IV of Fig. 1;

Fig. 3 is a view in sectional side elevation on an enlarged scale of an improved construction in accordance with the invention incorporated in the lower part of the constructional embodiment shown in Fig. 1;

Fig. 4 is a view in sectional side elevation of further modifications incorporated in the upper portion of the device shown in Fig. 1, and

Figs. 5 and 6 are diagrammatic views showing the electrical connections effected by the switch arrangement shown in Fig. 3 in its two operative positions or settings.

Referring first to the construction shown in Figs. 1, 1a, 1b, 1c, 1d and Fig. 2, the device illustrated comprises a substantially cylindrical body 1 of aluminium or other suitable metal, the lower end of which is flared or extended to form a base or foot. This end of the body 1 is provided with a ring member 2 of moulded plastic or other suitable material serving to secure in position a lens or cover glass 3 and a parabolic reflector 4, the ring member 2 being screw threaded into the flared lower end of the body 1 as indicated.

A screw threaded metal lamp shell 5 is mounted in the apex of the reflector 4 and encloses a plastic lamp bulb holder 6 for the lower lamp bulb 7. When this lamp bulb is in position in the holder 6, its outer terminal or shell 5 is in electrical contact with the reflector 4, while the centre pin or terminal of the lamp bulb abuts against a metal disc 8 mounted on the lower face of a plastic cup 9. As shown more clearly in Fig. 2 the cup 9 is secured

2

in the body 1 by rivets 10 and the disc 8 is provided with a stamped out tongue 11 engaging with the central pin of the lamp bulb 7.

A metal strip 12 is mounted on the upper face of the cup 9, the positive terminal or stud 13 of a dry battery 14 contained in the body 1 abutting against the strip 12. The disc 8 and the strip 12 are electrically connected together and secured to the cup 9 by means of rivets and the side wall of the cup 9 has a rectangular slot, as shown in Fig. 2, to accommodate a metal slider 15, which is arranged to make electrical contact in one of its extreme positions with the reflector 4, or, in its other extreme position with the disc 8, the slider, when in its intermediate position, not affecting either of these contacts.

At the opposite or other end of the body 1 a cylindrical cap of transparent plastic 16 or other suitable material is provided and serves as a shade or lens when the device is employed as a table lamp. Mounted within the cap 16 is a disc 17 of plastic or other insulating material on the lower face of which a metal cup 18 is adapted to abut against the central terminal or pin of an upper lamp bulb 19, a helical spring 20 being interposed between the cup 18 and the negative end or terminal of the battery 14.

The metal shell or outer terminal of the lamp bulb 19 is screw threaded into a metal shell or socket member 21 which is electrically connected to the casing 1 by a metal strip 22.

One end of a metal strip 23 is connected to the cup 18, this strip extending along the interior of the body 1 and being insulated therefrom as indicated at 24. The switch controlling the supply of current to the lamps 7 and 19 is housed in a casing 25 fixed on the body 1, a push button or knob 26 being slidably mounted on the casing 25. Within the casing 25 is a spring member 27 having a projection at its centre. The button 26 is provided with two arms 28, 29 (see Fig. 2) which extend through slots in the casing 25 and are secured to the slider 15 which is operated by the button 26.

The outer surface of the cylindrical body 1 is formed with a plurality of fine vertically extending flutes or grooves 33 interrupted by relatively wide and smooth vertical bands 34 and circumferential bands 35, which, in addition to providing an attractive appearance, also enable a good slip-free hand grip.

The operation of the device is as follows:

With the switch in the position shown in Fig. 1 neither the lamp 7 nor the lamp 19 is illuminated but when it is desired to use the device as a hand torch the push button 26 is moved into the position shown in Fig. 1c so that a circuit is completed from the positive terminal 13 of the battery 14 through contact strip 12, disc 8, the central pin of lamp 7, the lamp filament, the outer shell of the lamp, reflector 4, slider 15, strip 23, cup 18 and spring 20 to the negative terminal of the battery 14. The lamp 7 is thus supplied with current, and the device operates as an ordinary hand torch.

When on the other hand the device is stood on a table or other horizontal surface with the flared end of the body 1 resting thereon as a base or foot, as shown in Fig. 1, the push button 26 may be moved to the opposite extreme position shown in Fig. 1d so that a circuit is completed from the positive terminal 13 of the battery 14 through the strip 11 and disc 8, the slider 15, the body 1, strip 22, the outer shell of lamp 19, the lamp filament, the pin or other terminal of the lamp, the cup 18, and the spring 20 to the negative terminal of the battery 14.

In the modified construction shown in Figs. 3 to 6 of the drawings, which modified construction incorporates the features of the present invention, the parts of the torch corresponding to like parts of Figs. 1-2 are, in order to facilitate comparison, denoted by similar reference numerals.

As shown in Fig. 3, the push button 26 comprises a hollow sheet metal member provided with a stud 30 made of plastic or other suitable material, this stud being capable of sliding inwards and being held in its normal position shown in the figure by means of a bow spring 31.

31. A projection 32 in the centre of the spring 31 abuts against a locking stud 33 sliding within a corresponding opening in the casing 25, the outer end of the stud 33 when in its normal position engaging in the opening in the casing 25 but being flush with the outer surface of the casing. The slider 15 shown in Fig. 1 is replaced by a bridging contact arm 34, which in the "off" position of the switch occupies the position shown in Fig. 5.

This arm 34 is arranged to co-operate with three fixed contacts 35, 36 and 37 mounted upon but insulated from the body 1 of the torch.

The fixed contact 35 is connected to and forms part of the conductor strip 23 while fixed contact 36 is connected to a metal disc 38 mounted on the inner face of the plastic cup 9. Fixed contact 37 is formed on one end of a metal strip 39 the other end of which makes contact with the reflector 4 of the lamp 7. The inner end of the stud 33 slides within a suitable aperture in the bridging contact arm 34 and is resiliently held in the position shown in Fig. 3 by means of a bow spring 40.

The push button 26 is mechanically coupled to the arm 34 by short arms or tongues formed on the inner edge of the casing of the push button 26, these arms extending through slits in the casing 25 as previously described.

The disc 38 has a dished cavity 41 containing a light spring 42 interposed between the base of the cavity 41 and a contact member 43 loosely mounted on a metal disc 44 secured to the outer face of the cup 9 and electrically connected to the disc 38 by metal rivets or the like 50. The inner or central contact or pin of the lamp 7 engages with the contact member 43 and is thus resiliently connected to the disc 38.

Referring now to Fig. 4, as shown in this figure the electrical connection between the outer terminal or shell of the lamp 19 and the body 1 of the torch is effected by a metal ring 45 having a lug 46 engaging with a metal plate 47 mounted on the outer face of the disc 17 and provided with a screw threaded socket for the lamp 19.

The operation of the modified device shown in Figs. 3 and 4 is as follows:

Under inoperative conditions, i.e. when both lamps 7 and 19 are unilluminated the push button 26 and contact arm 34 occupy the position shown in Fig. 3 and are prevented from being accidentally displaced from this position by the locking stud 33 engaging with the side edges of the opening in the casing 25.

When it is desired to use the device as a table lamp the stud 30 must be first depressed to move the stud 33 out of engagement with the casing 25. The push button 26 can then be slid towards the lamp 19 to cause the contact arm 34 to assume the position shown in Fig. 5. A circuit is then completed from the positive terminal of the battery 14 through disc 38, fixed contact 36, contact arm 34, push button 26, the metal shell 1 of the torch, ring 45, disc 47, lamp 19 to the negative terminal of the battery 14.

In order to extinguish the lamp 19 it is only necessary to move the push button 26 downwards, i.e. away from the lamp 19 to the position shown in Fig. 3 in which the push button is again automatically locked by the stud 33 which reengages in the aperture in the casing 25.

When it is desired to use the device as a hand torch, the push button 26 is again released by depressing the stud 30 and is displaced in the opposite direction in order to bring the bridging contact arm 34 into the position shown in Fig. 6. A circuit is then completed from the positive terminal of the battery 14 through disc 38, disc 44, contact 43, lamp 7, reflector 4, strip 39, fixed contact 37, contact arm 34, fixed contact 35, strip 23, cup 18 to the negative terminal of the battery 14.

If desired, the lens cap 16 utilised in all forms of the invention may be made of transparent or translucent material or coated with phosphorescent material so that the position of the device can be readily observed even in darkness.

What I claim and desire to secure by Letters Patent is:

1. A portable electric illuminating device supplied by a dry battery and comprising a tubular body to receive the dry battery, one end of said tubular body being formed so as to constitute a foot or base on which the device can stand on a supporting surface such as a table, two electric lamp bulbs fitted respectively one at each end of said body portion, means for electrically connecting said lamp bulbs to said battery, said means comprising two alternative energising circuits each of which is associated with one of said lamp bulbs, and a switch for selectively controlling the supply of energising current from said battery to one or other of said alternative circuits to illuminate the lamp bulb associated therewith, 15 said switch having a neutral position in which it disconnects both of said alternative circuits from said battery, a fixed casing mounted on the outside of and extending outwardly from said tubular body, a bridging contact arm slidably mounted on the inside of said fixed casing, 20 outwardly of said tubular body, said arm constituting the movable part of said switch, a push button slidably mounted on said fixed casing and mechanically coupled to said bridging contact arm, and a locking device for normally retaining said bridging contact arm in a neutral or "off" position, said locking device comprising a stud fixed on said bridging contact arm so as to be movable therewith and normally engaging in an opening in said fixed casing, spring means carried on said bridging contact arm and acting on said stud in a direction 25 to press it into said opening, and means for releasing said stud from said opening when it is required to move the switch into either one of its two "on" positions, said release means comprising a stud slidably mounted in said push button in permanent alignment with said locking stud.

2. A device as claimed in claim 1 in which said tubular body is made of metal and further comprising a metal reflector for one of the lamp bulbs and three fixed contacts with which said bridging contact arm is arranged to co-operate, one of the said fixed contacts being connected 30 to said reflector, a second fixed contact being connected to the positive terminal of said battery, and the third fixed contact being connected to the negative terminal of the battery, the arrangement being such that said bridging contact arm, according to its position, effects electrical connection between the body of the torch and the said second fixed contact, or alternatively, electrical connection between the first and third fixed contacts, substantially as described.

3. A device as claimed in claim 1 in which said tubular body is made of metal and further comprising a metal reflector for one of the lamp bulbs and three fixed contacts with which said bridging contact arm is arranged to co-operate, one of the said fixed contacts being connected to said reflector, a second fixed contact being connected to the positive terminal of said battery, and the third fixed contact being connected to the negative terminal of the battery, the arrangement being such that said bridging contact arm, according to its position, effects electrical connection between the body of the torch and the said second fixed contact or, alternatively, electrical connection between the first and third fixed contacts, the electrical connection between the second fixed contact and the positive terminal of the battery 35 comprising a spring pressed contact member disposed between so as to connect electrically an adjacent lamp terminal and the said positive terminal of the battery.

4. A device as claimed in claim 1 in which said tubular body is made of metal and further comprising a metal reflector for one of the lamp bulbs and three fixed

contacts with which said bridging contact arm is arranged to co-operate, one of the said fixed contacts being connected to said reflector, a second fixed contact being connected to the positive terminal of said battery, and the third fixed contact being connected to the negative terminal of the battery, the arrangement being such that said bridging contact arm, according to its position, effects electrical connection between the body of the torch and the said second fixed contact or, alternatively, electrical connection between the first and third fixed contacts, the electrical connection between the second fixed contact and the positive terminal of the battery comprising two metal plates or discs secured on opposite sides of an insulating member and electrically connected together, one of said plates being in electric contact with the positive terminal of the battery and the other plate being formed with an aperture, a cup-shaped contact member formed with a flange which seats on the edge portion of said aperture so as to depend therefrom above the terminal of the lamp bulb associated with said reflector and a spring located on said cup-shaped member and bearing at one end on said plate which is in contact with said positive battery terminal, and operating to press said cup-shaped contact member into electrical contact with said lamp bulb terminal 25 which terminal is connected through said reflector with the fixed contact connected to said reflector.

5. A device as claimed in claim 1 in which said tubular body is made of metal and further comprising a metal reflector for one of the lamp bulbs and three fixed contacts with which said bridging contact arm is arranged to co-operate, one of the said fixed contacts be- 30

ing connected to said reflector, a second fixed contact being connected to the positive terminal of said battery, and the third fixed contact being connected to the negative terminal of the battery, the arrangement being such that said bridging contact arm, according to its position, effects electrical connection between the body of the torch and the said second fixed contact, or alternatively, electrical connection between the first and third fixed contacts, the electrical connection between said third fixed contact and the negative terminal of the battery comprising two metal contact members in electrical contact with one another and disposed respectively on opposite sides of an insulating plate, one of said contact members being in electrical contact with said third fixed contact and the other said contact member being formed with a screw-threaded aperture to receive one of said lamp bulbs, and a metal spring disposed between and bearing against said last mentioned contact member and against the negative terminal of the battery.
